Primary Examiner — Kimberly Barnes*Assistant Examiner* — Sarah A Nguyen(74) *Attorney, Agent, or Firm* — Jose Cherson Weissbrot(57) **CLAIM**

The ornamental design for a telescopic dish rack, as shown and described.

DESCRIPTION

FIG. 1 is a first perspective view of a telescopic dish rack showing my new design in a fully extended state;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the telescopic dish rack; and,

FIG. 10 is an enlarged view of the selected portion in FIG. 1.

The broken lines shown in the drawings depict portions of the telescopic dish rack that form no part of the claimed design.

1 Claim, 10 Drawing Sheets(56)
